UNITED STATES PATENT OFFICE

JOSEPH O'HANLON, OF BROOKLYN, NEW YORK

FIRE NOZZLE

Application filed June 27, 1928. Serial No. 288,743.

This invention is in a fireman's nozzle and is particularly concerned with a nozzle to be attached to the end of a hose or a pipe to cause discharge of water at an angle to the hose. Another object of the invention is to produce a fireman's nozzle which has no back pressure.

The profession of fire-fighting is unique in the character of the problems it faces. No two buildings are alike nor were there ever two fires in them which were alike. Nowhere else can one find the ever changing situations, the unexpected conditions calling for instant cool decision and adaptation of attack in spite of excitement, heat, gas and smoke. Nowhere else must the delivery and direction of a stream of water be changed without the loss of appreciable time, as must take place in effective fire-fighting. The entire character of a fire may change several times within as many minutes, and experienced fire-fighters know it is impossible to tell with what they will be faced from one minute to the next. Few tools actually are able to qualify under these severe conditions. The tools must be simple, portable, of universal applicability and highly efficient. In the field of the present invention—namely the nozzle used on the end of the hose line—there has been practically no change for many years, despite the obvious inadequacy of the nozzles now used.

According to the best practice the first engine company to reach the scene of a fire is generally supposed to take a line of hose into the building, and if possible to direct the stream of water onto the heart of the fire and to follow the fire in its course of travel. This line must be stretched in without a second's hesitation or consideration of conditions. This stretching of hose is ordinarily a matter of routine and the company is in the building almost instantly looking for the blaze. Heretofore entry has been made with a so-called controlling or valve nozzle on the end of the line. One example of this type of nozzle is shown in the U. S. patent to Hansen 1,236,297, dated August 7, 1917. This nozzle reduces the diameter of the stream from say 2 1/2 inches to 1 1/4 inches, and projects only

a straight stream. It consists of a nozzle portion which reduces the diameter of the stream, attached to the end of the hose, a valve portion having a controlling handle, and a tip on the outer end.

In fire-fighting, access to the seat of the fire is frequently not obtainable, either because the fire is too dangerous, or because it is in concealed spaces of the building, or separated from the firemen by a wall, floor or ceiling. If the seat of the fire is easily accessible, the controlling nozzle has proved to be a fairly efficient tool at nozzle pressures up to 50 or 60 pounds, especially because the valve in the nozzle enables the firemen to shut off the stream of water without sending a messenger back to the pumping engine or hydrant, which may be several blocks away from the fire. However, when access to the fire has to be gained by means of changing the direction of the stream relative to the hose, the plain and controlling nozzles are useless because they can throw only straight streams. No suitable tool for throwing the stream at an angle to the hose has yet been designed which in any way approaches the efficiency of the controlling nozzle. The need of changing the direction of the stream relative to the hose arises in cellar fires and sub-cellars, fires in adjoining rooms, fires in cocklofts, fires under floors, or in walls, partitions and ceilings. Various tools have been designed to take care of these situations, but no one tool is of universal applicability and none has the efficiency of a straight nozzle.

Thus, as frequently happens, one of the companies responding on a first alarm goes into the building, and after fighting the flames for a few minutes discovers that although they cannot get into the cellar it is necessary to throw the stream of water into the cellar in a horizontal direction. It is then necessary to send word back to the pumping engine, shut off the water, take off the controlling nozzle, screw on a so-called bent cellar pipe, or perhaps a cellar pipe such as shown in the patent to Baker No. 535,478 dated March 12, 1895, thrust the device through a hole cut in the floor, and then send word back to the engine to start pumping.

again. The shutting off of the stream while these changes are being made frequently permits spread of the fire, because the change is generally made at a crucial moment in the battle against the flames. These cellar devices, when attached, are not capable of throwing a satisfactory stream and heretofore the firemen have been badly handicapped whenever a straight nozzle could not be used.

10 In order to take care of all the various situations in which it is necessary to throw the stream at an angle to the hose, the average fire department has to carry at least four or five different tools, each for a slightly different situation. None of these devices has an hydraulic efficiency approaching that of a straight nozzle, nor am I aware of any tool that can be used to throw a solid stream on a cellar fire and which can be put on the hose line without shutting down the pressure at the engine. Neither am I aware of any tool which is adapted to meet all conditions in which it is desired to throw a stream at an angle to the hose. Nor do I know of any such tool which also may be used with equal effectiveness to throw a straight stream.

It is an object of my invention to provide a universal fireman's nozzle for use in directing an effective stream at an angle to the part 30 of the hose held by the fireman, and also capable of effective use when the stream is to be directed straight ahead.

Another object is to provide a fireman's tool which will not decrease the hydraulic 35 efficiency and which will reduce back pressure, thus permitting easier handling under higher pressures.

It is also an object of this invention to provide a coupling peculiarly suited to connect a fireman's tool to the tip of the usual 40 nozzle and to provide a new nozzle tip adapted to co-operate with the same coupling to permit quick attachment of the tool to the nozzle.

45 A preferred embodiment of the invention is described hereinafter and is illustrated in the accompanying drawings.

In the drawings—

Figure 1 is a vertical section through the 50 floor of a building showing the complete device in position to direct a stream under a floor onto a cellar fire;

Figure 2 is a view on a larger scale of the tool showing one way of attaching it to the 55 usual nozzle;

Figure 3 is a view of a modified connection between the tool and the nozzle showing a nozzle tip especially designed to co-operate with the coupling;

60 Figure 4 is a view in elevation of a complete tool detached from the nozzle;

Figure 5 is a top plan view of the same;

Figure 6 is a cross sectional view of the tool taken on the line 6—6 of Figure 4;

65 Figure 7 is a longitudinal sectional view

of the joint between the flexible tube 12 and the rigid section 13 of the tool; while

Figure 8 is a detail of the flexible tube when bent.

The nozzle and bracing means 15, 16 itself 70 comprises a tip 10, which may be identical with the tip used on the usual nozzle, a union 11, a flexible metal tube 12 secured at one end in the union 11, a coupling 14 on the other end of the nozzle. If desired there may be a 75 section of rigid tubing 13 between the tube 12 and the coupling 14. The flexible tube 12 may be of a known type. It has internal circumferential grooves which are shown as 80 helical. In the example shown in the drawings the length of the tube is such as to give a bend of 90° or thereabouts, and may, if desired, be between 18 and 24 inches. Such a 85 length of tube 1 1/2 inches in diameter, when bent uniformly, gives a uniform radius of curvature equal to more than two and one half diameters of the pipe, it being found that for best hydraulic efficiency such a minimum ratio is necessary.

A brace consisting of two rigid bars 15, 90 16 connects the union 11 and the end of the rigid tubing 13 near the flexible tube 12. The bars are mounted to swing about studs 17, 18 on either side of the union 11 and, at their other ends, have longitudinal slots 19 which 95 take over studs 20, 21 on the end of the rigid tubing 13. Clamping screws 22, 23 engage threads on the ends of studs 20, 21 and, when 100 screwed against the bars 15, 16, hold the bars firmly. This brace permits the flexible tube 12 to be bent and kept at any desired angle or to be left straight, and makes the flexible tube and the rest of the nozzle a rigid portable unit.

At an intermediate point on the brace is 105 a U-member 24 having arms 25, 26 swingably mounted on the bars 15, 16 respectively. A yoke 27 is attached to the center of the cross bar of member 24 by a nut 28 threaded on a shank extending from the yoke through the cross bar. A pin 29 extends through holes in the side pieces of the yoke 27 and is threaded to receive a nut 30 which holds it in place. A chain 31 is attached to pin 29 and to a bar 32 so that the tool may be suspended through a hole in a floor as shown in Figure 1. The bar and chain may be used in other ways as will be mentioned further on where the uses of the tool are described in greater detail.

110 The coupling 14, shown best in Figure 2, is designed for use with the standard nozzle tip 33 of a controlling nozzle 34 of the sort shown in the Hansen patent mentioned above. This nozzle is in general use in practically 115 all fire departments and almost always has a bead 35 of some sort at the discharge end of the tip.

120 The coupling consists of a sleeve internally threaded to fit on the threaded end of the 130

- rigid tubing. One end is of greater external diameter, as at 36, and has three equally spaced tapped holes in which clamping screws 37 are threaded. Two of these screws have shoulders at such a distance from their inner ends that when screwed against the portion 36 the screws position the tip 33 with its axis in line with the coupling axis. The third screw is then turned down against the tip to secure it in place.
- 5 A gasket 38 is provided to rest against the end of tubing 13. The nozzle tip and the coupling are brought together with the end of the tip against the gasket 38. Screws 37 are then turned down to engage the tip in back of the bead 35. Before the screws are fully down, the coupling should be turned relatively to the tubing 13 to draw the tip tightly against the gasket and to bring the 10 screws close up to the bead. This makes the joint watertight.
- 10 A modification is shown in Figure 3. In it, a special tip 40 is used having, instead of a bead at its discharge end, a threaded portion 41 of enlarged diameter to fit the coupling 14. The same coupling 14 with the clamping screws 37 is used, although the screws are not needed. When this special tip is used, it is carried as part of the flexible nozzle and the controller nozzle 34 is provided with the usual tip 33. When the tool is to be put on the hose line, the valve in the nozzle 34 is closed, the tip 33 removed, and the tool with tip 40 is put on in its place.
- 15 20 25 30 35 40 45 50 55 60 65 70 75 80 85 90 95 100 105 110 115 120 125 130
- To facilitate this the tip 40 has a swivel union 42 threaded to engage the stem of the nozzle 34 from which tip 33 was removed. This permits attachment of the tool without turning it bodily.
- If the tip 33 has become jammed so that it can not be removed, or if the threads on the tip 40 are not the same as those of the nozzle, as sometimes occurs, the special tip 40 may be removed from the coupling 14 with no difficulty and the tool may be attached to tip 33 by the screws 37 as in Figure 2. The attachment of the tool by removing the usual tip and replacing it with a special tip carried with the tool has certain advantages in point of speed if the tip 33 is not jammed. If it does jam, little time is lost in resorting to the screw clamp coupling. The coupling to the special tip has certain advantages in that it provides a threaded joint.
- A further modification of the tool is shown in Fig. 4. The rigid tubing 13, which serves principally as a spacer, need not be always as long as is shown in Fig. 1. The length there shown permits the flexible portion 12 to extend below the floor without bringing the controlling nozzle, which must be operated by the firemen, into the opening in the floor. In other situations, it is desirable to have the tool as short as possible. To accommodate both needs a removable rigid section 45 is provided. A coupling 46 similar to coupling 14 is put at the end of the flexible tube 12 so that it may be attached directly to the nozzle tip or to the rigid spacer section 45. The spacer section 45 has a similar coupling 47 at one end for attachment to the nozzle tip when the spacer itself is coupled to the flexible tube. Spacers of various lengths may be provided if desired.
- It will be noted from the relative dimensions of the example shown, that all parts of the tool may have an internal diameter substantially equal to that of the discharge end of the tip 33 and that this diameter is less than that of the hose line. The tool therefore provides in effect a cylindrical extension of the minimum diameter of the standard controlling nozzle. The tip 10 at the end of the tool is slightly convergent internally to an inch and a quarter and may serve to form the jet as it leaves the tip.
- The outstanding merit of the tool described above is its capability of effective use under the most difficult and varied conditions. It is found that when the flexible tube is bent, the hydraulic efficiency is not noticeably different from that obtainable with the flexible tube straight. A notable advantage present with this tool, whether bent or straight, is that much higher pressures may be used than with the controlling nozzle or with the so-called "play pipe" than heretofore possible. The nozzle seems to have substantially no back pressure compared to any other nozzle and as a result the line can be handled by fewer men at higher pressures.
- Probably the most common need for a tool to throw a stream around the corner is in fighting cellar fires. With the new tool a stream can be delivered the full length of the average cellar, making it unnecessary for anyone to enter the cellar and to expose himself to the dense smoke and gas commonly present with such fires. The tool may be introduced into the cellar through a hole in the floor to deliver a stream either lengthwise or crosswise of the beams, or it may be introduced through a window, hatchway or other opening when it is not possible to reach the floor and to make a hole in it.
- The tool is of equal value in fighting fires within walls or between partitions or in hallways where the heat or limited space prevents direct approach to the fire. A similar use is found where a wall has been breached, but because of heat, men cannot pass through. A stream may be put directly through the breach and also along the walls, the nozzle being held on the safe side of the breach. A similar condition is met in roof fires when the hose is brought up over the coping. If the men cannot go onto the roof, the tool may be bent and a stream may be delivered directly to the blaze. In ship or dock fires the tool makes possible effective delivery of the stream

through portholes, or hatchways, or under the pier.

The chain attached to the brace bars acts as supporting means and permits mounting in other ways than that shown in Figure 1. For instance, it may be desired to throw a stream from one building into another across a street or yard. The flexible tube may then be set straight, resting on a window sill, and the chain secured outside the window.

The brace bars not only serve to hold the tool in the desired bent or straightened position but they also prevent twisting of the flexible section. These bars and the cross member 24 act as a nozzle holder and afford a convenient means by which the tool may be grasped and held while in use under conditions which do not require that the tool itself be close to the fire. It will be obvious that other bracing means can be used to make the flexible tube rigid.

The metal tubing preferably used for the flexible tube is fireproof and very rugged so that it is admirably suited to the work. Its spiral "i. e. helical" construction may, it is thought, be an element contributing to the high hydraulic efficiency of the tool, whether bent or straight. These shallow circumferential grooves have a beneficial influence in reducing the back pressure. It is also thought that when the nozzle is bent, based on the assumption that the spirally wound overlapping material gives a slight whirl to the water, although none is apparent in the issuing jet, the spaces 48 between laps 49 on the outer wall of the bend pocket the water and present, over a considerable area, a practically frictionless surface to the stream. (Figure 8.) When these grooves are made helical the pitch is very rapid, the distance between consecutive grooves measured longitudinally of the tube preferably being considerably less than the diameter of the tube.

It will be apparent that while many advantages of the device are due to the fact that it can be bent or left straight many of its advantages would be present if the device were not adjustable. The flexible tube, however, adds greatly to the number of uses to which the tool may be put since the hydraulic efficiency is practically the same whether the tool is bent or not, and the tool may be kept on the nozzle after the "around the corner" work is done. The ease with which the device may be held even under high pressures is a merit which is present both when the tool is straight and when bent.

No attempt is made here to explain the theory of the device or to account for all of its characteristics such as the high hydraulic efficiency and apparent practical elimination of so-called back pressure.

It is clear that many variations in details are possible without departure from the substantial scope of the invention as defined in

the following claims. Where in the claims I speak of hose it should be understood to include a flexible hose or a rigid pipe, whether portable or in a fixed mounting.

I claim:—

1. A fire nozzle comprising a tip, a spirally wound flexible metallic tube on said tip of diameter substantially equal to the internal diameter of the tip, and a coupling on the other end of the tube, in combination with adjustable support means attached to the tube adjacent each end adapted to fix the distance between the ends of said tube. 70

2. A fire nozzle in accordance with claim 1 in which support means are rigid and attached to the ends of the tube at the side of the latter. 80

3. A fire nozzle comprising a flexible metallic tube in combination with adjustable rigid support means on both sides of said tube and attached to the tube adjacent the ends thereof adapted to fix the distance between the points of attachment. 85

4. A fire nozzle comprising a spirally wound flexible metallic tube and rigid means constructed and arranged to be secured adjacent the ends of said tubes to hold the latter in bent or straight position, in combination with supporting means secured to said rigid means at a point intermediate their ends. 90

5. A fire nozzle comprising a flexible metallic tube, a coupling attached to one end of said tube, adjustable rigid support means connecting the ends of said tube adapted to make a rigid unit of the entire nozzle and a tapered tip on the other end of said tube. 95

6. A fire nozzle, comprising a flexible metallic tube, and a threaded coupling on one end thereof adapted to receive a conjugate threaded male element, in combination with a tapered tip adapted to gather the stream on the other end of the tube and of substantially the same internal diameter as the tube. 105

7. A fire nozzle comprising a metal tube whose interior is grooved circumferentially, the distance between consecutive grooves measured longitudinally of the tube being less than the diameter of the tube, in combination with a coupling on one end of said tube, and a tapered tip on the other end of said tube adapted to gather the stream. 110

8. A fire nozzle comprising a helically wound flexible metallic tube of uniform diameter in which the helical windings form grooves on the inside whose pitch is less than the diameter of the tube, in combination with a tapered tip to gather the stream on one end of the tube and a coupling on the other end. 120

9. A fire nozzle having a tapered tip to gather the stream together, in combination with a flexible metallic tube of uniform internal diameter of the order of the tip to which it is attached, and a hose connection on the other end of the tube. 125

10. A fire nozzle having a tapered tip to 130

gather the stream together, a metallic tube of uniform internal diameter of the order of that of the tip to which it is attached, the interior of said tube having grooves, each 5 groove circling the tube in a distance less than the diameter of the tube.

11. A fire nozzle having a tapered tip to gather the stream together, a metallic tube of uniform internal diameter of the order of that of the tip to which it is attached said 10 tube having a minimum radius of curvature of more than two and one-half times its internal diameter, and a straight connection on the other end of the tube for attaching to a 15 hose substantially greater in diameter than the tube.

12. A fire nozzle comprising a coupling, in combination with a flexible metallic tube attached thereto at one end, the minimum radius of curvature of said tube being more 20 than two and one-half times the internal diameter of the tube and the length of said tube being such that it may be bent to a curve of 90°, a tapered tip on the other end of said 25 metallic tube, and adjustable support means permitting the tube to be bent throughout its length and making a rigid unit of the nozzle.

13. A fire nozzle comprising a flexible metallic tube, a coupling on one end of said tube and a tapered tip on the other, in combination 30 with adjustable support means attached to the tube adjacent each end, permitting the tube to be bent throughout its length and fixing 35 the distance between the ends.

14. A fire nozzle having a tapered tip to gather the stream together, a flexible metallic tube of internal diameter of the order of the tip to which it is attached, said tube being 40 formed of helically wound over-lapping material forming recesses on the interior of the tube whose width is varied as the tube is flexed.

15. A fire nozzle having a tapered tip to 45 gather the stream together, in combination with a tube of uniform diameter of the order of the tip to which it is attached, said tube having a uniform minimum radius of curvature throughout its length.

50 16. A fire nozzle having a tapered tip to gather the stream together, a flexible metallic tube of internal diameter of the order of the tip to which it is attached, said tube being 55 formed of helically wound overlapping material forming recesses on the interior of the tube whose width is varied as the tube is flexed, together with a straight connection on an end of the tube for attaching a hose.

56 17. A fire nozzle having a tapered tip to 56 gather the stream together, in combination with a flexible metallic tube of uniform diameter of the order of the tip to which it is attached, said tube having a uniform maximum curvature throughout its length.

65 18. A fire nozzle comprising a tapered tip

to gather the stream and a flexible metallic tube attached thereto, in combination with support means attached to the tube adjacent each end and making the nozzle a rigid unit.

In testimony whereof I have signed my 70 name to this specification.

JOSEPH O'HANLON.
